BABY JUMPER

Wayne W. Call and Lucille W. Call, Afton, Wyo.

Application December 4, 1950, Serial No. 198,988

2 Claims. (Cl. 155—20)

1
This invention comprises novel and useful improvements in a baby jumper and more specifically pertains to an apparatus for resiliently supporting the body of a child and facilitating the exercising or jumping of the child.

The primary object of this invention is to provide an improved baby jumper or exerciser which shall have an improved and easy adjustment for regulating the height of the apparatus to accommodate infants of different size; which shall have an improved seating or supporting member attached to the device in a removable and improved manner; and in which the seat shall comfortably conform to and embrace the body of a child and yet may be readily removed for servicing, cleansing or the like.

These, together with various ancillary features and objects of the invention, which will later become apparent as the following description proceeds, are attained by the present invention, a preferred embodiment of which has been illustrated, by way of example only, in the accompanying drawings, wherein:

Figure 1 is a view showing one embodiment of apparatus incorporating therein the principles of this invention;

Figure 2 is a fragmentary plan view of a portion of the seat portion of the device;

Figure 3 is an exploded perspective view of a portion of the cross bar and the supporting strap of the seat portion.

Referring now more specifically to the accompanying drawings, wherein like numerals designate similar parts throughout the various views, it will be apparent that the apparatus forming the subject of this invention consists of a resilient supporting means together with a removable seat portion.

The supporting means preferably comprises a tension spring 10 of any desired character and which is adapted to be supported by a hook 12 secured to an overhead beam or the like 14, an adjusting strap 16 of any desired character being provided with a pair of snap-catches or self-closing hooks 18 at its ends adapted to respectively engage the lower end of the spring 10 and a supporting ring 20 is secured to the mid-portion of the cross-beam 22. The latter may be constructed of any desired material, and especially of wood or the like, and as shown in Figure 3, has its opposite ends longitudinally slotted as at 24 to provide bifurcated end portions 26. These end portions are provided with aligned vertically disposed apertures 28 adapted to receive a fastening bolt 30 having a wing nut 32. By means of the

5
bolt and wing nut, the slots 24 are closed to thereby releasably retain in the slots the intermediate looped portions 34 formed at the mid-portions of a pair of straps 36 as by seaming the same or stitching the same in a manner shown at 37 in Figure 3.

The depending parts of the straps provide supporting bands 38 and 40 which, at their lower ends, are respectively secured to the front and rear portions of a flexible belt 42 which is adapted to encircle the body of a baby and may be constructed of any desired material. Although not limited thereto, the belt may conveniently be formed of rubber, canvas, khaki or similar materials. The upper edge of the belt is notched or cut away as at 44 to provide a pair of recesses adapted to comfortably receive the arms of the infant.

10
The seat portion further includes a crotch strap 46 whose rear end is stitched or otherwise fixedly secured to the mid-portion of the rear part of the belt 42, this strap being adapted to be passed through the crotch of the infant and being secured to the front portion of the belt by safety pins or the like as shown at 48.

15
From the foregoing, it will be apparent that by removing the bolts 30 and wing nuts 32, the supporting straps 36 together with the seat portion may be readily removed from the cross arm 22 to facilitate cleaning or servicing of the seat portion. Further, the strap or belt 46 may be readily varied in length by the buckle of the same to properly position the device at any desired elevation to accommodate different sizes of children.

20
From the foregoing, the construction and operation of the device will be readily understood and further explanation is believed to be unnecessary.

25
However, since numerous modifications and changes will readily occur to those skilled in the art, it is not desired to limit the invention to the exact construction shown and described, and accordingly all suitable modifications and equivalents may be resorted to, falling within the scope of the appended claims.

30
Having described the invention, what is claimed as new is:

35
1. A baby jumper comprising a resilient support and a flexible baby seat mounted on said support, said support including a cross bar, straps securing the ends of said cross bar to said flexible seat, the ends of said cross bar having open ended slots, said straps having closed loops at their mid-portions received in said slots and closely surrounding adjacent portions of said

cross bar; removable fasteners connecting together portions of said cross bar disposed on opposite sides of said slots for closing the open ends of said slots and retaining said straps in said slots.

2. A baby jumper comprising a resilient support and a flexible baby seat mounted on said support, said baby seat comprising a flexible band for embracing the body of a baby, a flexible crotch strap secured to said flexible band at the rear of said seat, a pair of supporting straps each having one end secured by common securing means to said flexible band above and adjacent said crotch strap connection, the other ends of said supporting straps being secured to 15 said flexible band in spaced relation at the front of said seat, removable securing means securing together the ends of said flexible band to form an endless band, said removable securing means also securing the other end of the crotch strap 20 to said flexible band, said support including a cross bar, said supporting straps securing the ends of said cross bar to said flexible seat, the ends of said cross bar having open ended slots, said straps having closed loops at their mid- 25 portions received in said slots and surrounding

adjacent portions of said cross bar, removable fasteners connecting together portions of said cross bar disposed on opposite sides of said slots for closing the open ends of said slots and retaining said supporting straps in said slots.
